ATTORNEYS.

UNITED STATES PATENT OFFICE.

HARRY LONG, OF KOKOMO, INDIANA.

DESIGN FOR A HEADLIGHT-LENS FOR AUTOMOBILES AND OTHER VEHICLES.

51,598.

Specification for Design.

Patented Dec. 18, 1917.

Application filed September 26, 1917. Serial No. 193,896. Term of patent 14 years.

To all whom it may concern:

Be it known that I, HARRY LONG, a citizen of the United States, residing at Kokomo, in the county of Howard and State of Indiana, have invented a new, original, and ornamental Design for a Headlight-Lens for Automobiles and other Vehicles, of which the following is a specification, reference being had to the accompanying drawing, forming a part thereof, in which—

Figure 1 is a plan view of a lens showing my invention, and,

Copies of this patent may be obtained for five cents each, by addressing the "Commissioner of Patents, Washington, D. C."

Fig. 2 is in part an edge view and in part a cross section of the same.

I claim:

The ornamental design for a headlight-lens for automobiles and other vehicles, as shown.

HARRY LONG.
